(57) **CLAIM**

The ornamental design for a mobile phone, as shown and described.

DESCRIPTION

FIG. 1 is a front view of a mobile phone showing the new design;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is a front perspective view thereof;

FIG. 8 is a back perspective view thereof;

FIG. 9 is a front view of the mobile phone of FIG. 1 shown in an unfolded state;

FIG. 10 is a back view thereof;

FIG. 11 is a left side view thereof;

FIG. 12 is a right side view thereof;

FIG. 13 is a top view thereof;

FIG. 14 is a bottom view thereof;

FIG. 15 is a front perspective view thereof;

FIG. 16 is a front perspective view thereof;

FIG. 17 is a front perspective view of the mobile phone of FIG. 1, shown in another unfolded state;

FIG. 18 is a front perspective view thereof;

FIG. 19 is a right side perspective view thereof;

FIG. 20 is an enlarged view of a portion of FIG. 17; and,

FIG. 21 is an enlarged view of a portion of FIG. 18.
